US0D1076837S

(12) **United States Design Patent** (10) Patent No.: **US D1,076,837 S**
(45) Date of Patent: ** May 27, 2025

(54) **BAFFLE**

(71) Applicant: **LAM RESEARCH CORPORATION**,
Fremont, CA (US)

(72) Inventor: **Emile Charles Draper**, Molalla, OR
(US)

(73) Assignee: **LAM RESEARCH CORPORATION**,
Fremont, CA (US)

(**) Term: **15 Years**

(21) Appl. No.: **29/882,800**

(22) Filed: **Jan. 19, 2023**

(51) LOC (15) Cl. **13-03**

(52) U.S. Cl.

USPC **D13/182**; D15/144; D15/138; D15/144.1

Primary Examiner — Elizabeth J Oswecki

(57) **CLAIM**

The ornamental design for a baffle, as shown and described.

DESCRIPTION

FIG. 1 is a top view of a baffle showing my new design;
FIG. 2 is a bottom view of the baffle shown in FIG. 1;
FIG. 3 is a front view of the baffle shown in FIG. 1;
FIG. 4 is a back view of the baffle shown in FIG. 1;
FIG. 5 is a right side view of the baffle shown in FIG. 1;
FIG. 6 is a left side view of the baffle shown in FIG. 1; and,
FIG. 7 is a perspective view of the baffle shown in FIG. 1.

1 Claim, 5 Drawing Sheets
